(57) **CLAIM**

The ornamental design for a display screen with graphical user interface, as shown and described.

DESCRIPTION

FIG. 1 is a front view of a display screen with graphical user interface showing a first embodiment of my new design; FIG. 2 is a second embodiment thereof; FIG. 3 is a third embodiment thereof; FIG. 4 is a fourth embodiment thereof; FIG. 5 is a fifth embodiment thereof; FIG. 6 is a sixth embodiment thereof; FIG. 7 is a seventh embodiment thereof; FIG. 8 is an eighth embodiment thereof; and, FIG. 9 is a ninth embodiment thereof.

The broken lines illustrate the display screen and portions of the graphical user interface, and form no part of the claimed design.
